(57) **CLAIM**

The ornamental design for a mobile storage system, as shown and described.

DESCRIPTION

FIG. 1 is a perspective view of a mobile storage system showing my new design;

FIG. 2 is a front elevational view thereof;

FIG. 3 is a back elevational view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is an enlarged perspective view of the upper front left side corner thereof;

FIG. 9 is an enlarged perspective view of the upper rear right side corner thereof;

FIG. 10 is an enlarged perspective view of the lower rear right side corner thereof;

FIG. 11 is a perspective view of a second embodiment thereof, the only difference being the removal of a vertical member;

FIG. 12 is a perspective view of a third embodiment thereof, the only difference being the addition of a vertical member;

FIG. 13 is a perspective view of a fourth embodiment thereof, the only difference being the addition of two vertical members; and,

FIG. 14 is a perspective view of a fifth embodiment thereof, the only difference being the addition of doors.

The broken line showing of shelves in FIGS. 1, 2, 12, 13, and 14 is for illustrative purposes only and forms no part of the claimed design.
